UNITED STATES PATENT OFFICE

150,538

DESIGN FOR A NECKLACE

Nicklos A. Bauer, Chicago, Ill.

Application August 8, 1947, Serial No. 140,774

Term of patent 14 years

(CL. D45—16)

To all whom it may concern:

Be it known that I, Nicklos A. Bauer, a citizen of the United States, residing at Chicago, in the county of Cook and State of Illinois, have invented a new, original, and ornamental Design for a Necklace, of which the following is a specification, reference being had to the accompanying drawings, forming a part hereof.

Fig. 1 is a front elevational view of a necklace, showing my new design.

The dominant features of the design reside in the portions shown in full lines on the drawing.

I claim:

The ornamental design for a necklace, as shown and described.

NICKLOS A. BAUER.
